HERBERT L. MEEDER, OF DENVER, COLORADO, ASSIGNOR OF THREE-EIGHTHES TO
LEWIS S. HALL AND TWO-EIGHTHES TO JOHN INGLIS, BOTH OF DENVER, COLORADO.

INTERNAL-COMBUSTION ENGINE.

1,410,946.

Specification of Letters Patent. Patented Mar. 28, 1922.

Application filed December 31, 1920. Serial No. 434,260.

To all whom it may concern:

Be it known that I, HERBERT L. MEEDER, a citizen of the United States, residing at the city and county of Denver, and State of 5 Colorado, have invented certain new and useful Improvements in Internal-Combustion Engines; and I do declare the following to be a full, clear, and exact description of the invention, such as will enable others 10 skilled in the art to which it appertains to make and use the same, reference being had to the accompanying drawings, and to the characters of reference marked thereon, which form a part of this specification.

15 The object of this invention is to provide a cylinder construction for internal combustion engines by means of which dilution of the lubricating oil in the crank case by gases escaping past the piston rings will 20 be avoided.

This is accomplished by means of a partition which separates and seals the crank case from the spaces below the piston, and by connecting the spaces below each pair of pistons, and in turn connecting said spaces with the atmosphere by means of a tube in order 25 to lead off the gases which get by the piston rings. With this construction the combined space below two adjacent pistons, which are 30 at opposite extremities of their strokes, remains constant, the air in said spaces being forced back and forth through the connection from beneath one piston to the space beneath the other.

35 In the drawings:

Fig. 1 is a vertical section through one cylinder and the crank case, showing the means for the escape of the gases which have worked past the piston, and the means for 40 oiling;

Fig. 2 is a vertical section at right angles to that of Figure 1, showing two adjacent cylinders and their connections.

A conventional crank case 10 carries the 45 cylinder block 12 provided with the usual water jacket 14, spark plugs 15 and valves 16. Within each cylinder 12 a piston 18 is mounted, the pistons being provided with the usual rings 20. Each piston 18 is provided 50 adjacent its central portion with a dependent skirt or sleeve 22, which closely fits an upstanding sleeve 24 carrying rings 25. A piston rod 26 extends upwardly through the sleeve 24 and is secured to the 55 piston as at 27. This rod 26 has a longi-

tudinally extending passage 28 which is in communication with the space above the sleeves 24 and below the piston 18 by means of an aperture 30, which relieves compression or suction within said space. 60

With this arrangement a space 32 is provided beneath each piston 18 and above the partitioning wall 36, which separates said space 32 from the crank case and which carries the upstanding sleeve 24. A passage 65 34 connects the two spaces 32 of adjacent cylinders so that the air may be forced through said passage from one cylinder to the other, as the pistons reciprocate. The two pistons in the adjacent cylinders are 70 oppositely disposed, so that when one piston is at one extremity of its stroke, the other piston is at the opposite extremity of its stroke. In this manner the combined spaces beneath the two pistons is constant. The 75 rings 25 on the upstanding sleeves 24 cooperate with the depending skirts 22 and prevent escape of air or gas from the spaces 32 to the space above the sleeves 24 and thence to the crank case. In this manner 80 dilution of the oil in the crank case by the gases which have worked by the rings 20 is avoided. In order to permit escape of said gases which have worked past the rings 20, a tube 35 is threaded into the cylinder 85 wall and this tube leads to the atmosphere. Thus, any surplus gas is permitted to escape from the spaces 32 and there is no danger of drawing outside air laden with dust or grit into said spaces. In this manner 90 the cylinder walls are kept clean and scoring by dust or grit is prevented. The pipe 35 may be inserted in the side of the cylinder, as indicated in Figure 1, or it may penetrate the cylinder wall at the passage 95 34, as indicated in Figure 2.

A plate 38 is positioned between the partitioning wall 36 and the crank case 10 and is provided with a depending guiding sleeve 40 for each piston 18, which guides the ring 100 42 carrying wrist pin 44, which connects the piston rod 26 with the connecting rod 45 driven from the crank shaft 46. In this manner each rod 26 reciprocates on a fixed longitudinal axis. 105

For the purpose of oiling the piston 18 and the skirt 22, an oil duct 50 is led into the cylinder wall 12, the end of the duct 50 projecting a short distance beyond the wall, as seen in Figure 1, so that the drops of oil 110

may be taken from the tip of the duct by the rushing air as it moves from one cylinder to the other. This duct 50 is supplied by any suitable means, such as from a reservoir 52 controlled by a needle valve 54. Oil is carried up from the crank case through a pipe 55 and is supplied by means of a pump 56 which may be conveniently operated by a cam on the cam shaft 58, which controls the 10 push rod 60 for the valve 16. The overflow pipe 62 conveniently leads to a ledge 64 on the guide 65 for the push rod 60, for the purpose of lubricating the latter.

From the foregoing it will be seen that I 15 have provided comparatively simple and highly efficient means for preventing dilution of the lubricating oil in a crank case by gases which work past the piston rings, and that I have provided such a device with efficient oiling means and means for escape of 20 said gases, which will prevent the entrance of dust or grit to the cylinders.

I claim:

1. In an internal combustion engine, a 25 pair of cylinders, a piston reciprocable in each cylinder, means to reciprocate the pistons in opposite directions from one another, a crank case below the cylinders, and means separating the spaces below the pistons from 30 the chamber within the crank case, said cylinders having an opening connecting the spaces below the pistons with each other.

2. In an internal combustion engine, a 35 pair of cylinders, a piston reciprocable in each cylinder, means to reciprocate the pistons in opposite directions from one another, a crank case below the cylinders, means separating the spaces below the pistons from the chamber within the crank 40 case, said cylinders having an opening connecting the spaces below the pistons with each other, and an opening connecting said spaces with the atmosphere.

3. In an internal combustion engine, a 45 pair of cylinders, a piston reciprocable in each cylinder, means to reciprocate the pistons in opposite directions from one another,

a crank case below the cylinders, means separating the spaces below the pistons from the chamber within the crank case, said cylinders having an opening connecting the spaces below the pistons with each other, and a tube leading to said cylinders and connecting said spaces with the atmosphere. 50

4. In an internal combustion engine, a 55 pair of cylinders, a piston reciprocable in each cylinder, means to reciprocate the pistons in opposite directions from one another, a crank case below the cylinders, means separating the spaces below the pistons from the chamber within the crank case, said cylinders having an opening connecting the spaces below the pistons with each other, and an oil tube leading to said cylinders to beneath said pistons to supply said spaces 60 with oil.

5. In an internal combustion engine, a crank case, a pair of cylinders, pistons in said cylinders whereby explosion chambers are provided above the pistons, means between the crank case and the spaces beneath the pistons to separate and seal said spaces from the crank case, means projecting through said separating means from the crank case into engagement with the pistons 70 to reciprocate the same in opposite directions from one another, and a connection between said spaces providing communication with each other. 75

6. In an internal combustion engine, a 80 pair of cylinders, a piston reciprocable in each cylinder, means to reciprocate the pistons in opposite directions from one another, a crank case below the cylinders, and means separating the space below the pistons from the chamber within the crank case, said cylinders having an opening connecting the spaces below the pistons with each other, and an oil tube projecting into said opening whereby oil may be taken from the tip of 85 said tube by the passing air currents. 90

In testimony whereof I affix my signature.

HERBERT L. MEEDER.
